UNITED STATES PATENT OFFICE

2,384,653

INDICATING DEVICE

Mark C. Smith, Chicago, Ill.

Application December 13, 1943, Serial No. 514,079

3 Claims. (Cl. 179—11)

In its broadest aspect, my invention relates to certain new and useful improvements in indicating devices and more particularly to a device for indicating, if desired, the number of times a telephone receiver is removed from and replaced upon its cradle, whereby the lessee of the telephone may at the end of any period, such for example, as the end of a calendar month, know how many telephone calls have been made. In this respect the invention has for its principal object the provision of an improved construction which will be highly efficient in use and economical in manufacture.

Among the salient objects of the invention is the provision, if desired, for indicating each time the receiver is placed upon its cradle, thereby enabling the lessee to substantially check the number of calls at any time.

A still further object of the invention is the provision of a device of this character having an arrangement whereby the indicating mechanism may be reset to zero position at the end of a pre-determined period or to render the indicating device inoperative in case of a "busy" signal or for any other reason.

A still further object of the invention is the provision of a device of this character wherein provision is made for the reception of the telephone cradle, the arrangement being such that the cradle will support the receiver in a position to operate the indicating mechanism, if desired, each time the receiver is placed upon the cradle.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention;

Fig. 2 is a plan view of the same taken substantially on line 2—2 of Fig. 1;

Fig. 3 is a sectional detail view taken substantially on line 3—3 of Fig. 2;

Fig. 4 is a sectional detail view of the same taken substantially on line 4—4 of Fig. 3;

Fig. 5 is a fragmentary sectional detail view taken substantially on line 5—5 of Fig. 3;

Fig. 6 is a fragmentary sectional detail view taken substantially on line 6—6 of Fig. 1; and

Fig. 7 is a fragmentary detail view taken substantially on line 7—7 of Fig. 2.

The drawings illustrate the preferred form of construction of my invention. This construction of the invention may vary in form without de-

parting from the spirit thereof. In this connection I provide a housing or enclosure 10, the top of which is provided by two cover sections 11 and 12. These cover sections 11 and 12 are secured to the side walls 13 of the housing 10 by suitable screw elements 14. The cover section 12 at one end thereof extends as at 15 above the major portion 16. This portion 16 of the cover section 12 has a recessed seat 17 formed therein. This seat 17 receives the base 18 of the cradle 19 of the telephone 20. This telephone 20 includes the receiver 21, normally supported on the cradle 19 and held from displacement therefrom by means of side lugs 22.

16 The bottom wall 23 of the housing has preferably countersunk therein a bearing 24. Journaled in this bearing 24 is a stud shaft 25, the exterior end of which has a finger knob 26 formed therein. The inner end portion 27 of 20 this stud shaft 25 is threaded into a washer 28, and this threaded end portion 27 carries a disc 29 having a spiral groove 30 formed therein with an entrance to the spiral as at 31. On the face of this disc 29 between the spirals, in numerical 25 order, are indicia 32, in the present instance in the form of numbers beginning with the number "1".

This disc 29 is preferably secured to a base disc 33 through the medium of suitable connecting elements 34. This base disc 33 on its peripheral edge is provided with ratchet teeth 35. These teeth 35 are adapted to be engaged by a pawl 36 hinged to a slidable bar 37 as at 38. Carried by this bar 37 is a leaf spring 39 bent 35 upon itself to provide an end portion 40 bearing against the pawl 36 to normally hold the pawl in engagement with the teeth 35.

In the wall 41 of the extended portion 15, there is formed an opening 42 in which there is mounted a suitable bearing 43. Projected through this bearing 43 is a pin 44 having a handle 45. This pin 44 is slidably positioned through a sleeve 46 formed in a plate 47 secured to the wall 48 of the extended portion 15. The lower end portion 49 of this pin 44 is adapted to engage a cam-shaped surface 50 formed on the pawl 36, whereby when the pin 44 is pressed downwardly against the action of a spring 51, this pin will engage the cam surface 50 and swing the pawl 36 against the 45 action of the spring 39 from engagement with the teeth 35, thus permitting the disc 29 to be rotated in an anti-clockwise direction to reset the numerals thereon with the numeral "1" exposed 50 to the observer, in a manner hereinafter set forth.

The cover sections 11 provide a groove 52 through which the numbers on the disc 29 are exposed. Movable longitudinally in this groove is a window 53. This window 53 is provided with opposite grooved edges 54 which receive the edges 55 of the cover sections 11. The window 53 carries a depending pin 56 which operates in the spiral groove 30 of the disc 29, whereby when the disc 29 is rotated, the window will be caused to move longitudinally in the groove 52. This will particularly take place when the disc 29 is moved in step by step movement in a manner now to be described.

Carried by the wall 48 is a plate 57. This plate 57 at its upper end portion carries a lateral pin 58 having a reduced portion 59 operating in an elongated slot 60 formed in an operating bar 61. The lower end portion 62 of this bar 61 by means of a pin connection 63 is connected to a bell crank 64. The bell crank 64 is pivotally connected as at 65 to the bar 31. The limb portion 66 of the bell crank 64 is pivotally connected to the wall 48 by means of a pin connection 67 in a manner such that when the operating bar 61 is moved downwardly, the bell crank 64 will pivot on the pin connection 67, and this pivotal movement of the bell crank 64 will slide the bar 31 in a direction against a leaf spring 68. This movement of the bar 31 will bring the pawl 36 into engagement with one of the teeth 35 and the movement is of such degree as will cause the disc 29 to rotate one step, bringing the next succeeding number into position within the window 53.

The leaf spring 68 (Fig. 2) is connected as at 69 to the side wall 70 of the housing.

The operating bar 61 at its upper end portion carries a rubber cap 71, and this bar is so formed as to dispose the rubber cap beneath the receiver 21 inwardly of the ear piece 72 whereby when the receiver 21 is placed upon the cradle 19, the weight of the receiver will press the operating bar 61 downwardly, and this movement of the bar 61 will pivot the bell crank 64 in the manner and for the purpose hereinbefore set forth.

The telephone seat 17 may be of any desired shape to accommodate various shapes of telephone cradles, and the length of the operating bar 61 and its shape may be varied to accommodate such different forms of telephone whereby to bring the cap 71 into engagement with the receiver or that part of the telephone which will cause the bar 61, under the weight of the receiver or other part of the telephone, to move downwardly for the reasons hereinbefore stated.

As stated herein, each time the receiver 21 is taken off the cradle 19, the operating bar 61, under the action of the leaf spring 68, will move upwardly, disposing the pawl-bearing bar 31 in a position with the pawl 36 about to engage one of the ratchet teeth 35. When the receiver is replaced upon the cradle, it will engage the rubber cap 71, and the weight of the receiver will move the operating bar 61 downwardly. On this movement of the operating bar 61 downwardly, the bell crank 64 will be caused to pivot in an anti-clockwise direction. In this movement of the bell crank 64, the bar 31 will be moved against the action of the spring 68 and in this movement of the bar 31 the pawl 36, being in engagement with one of the ratchet teeth 35, will move the disc 29 one step, bringing the next succeeding number 32 within the area of the window 53. The lessee of the telephone, by observing the number exposed through this window 53 may de-

termine how many times the telephone has been used.

At the end of a predetermined period, by pressing the pin 44 downwardly to bring the end 49 thereof into engagement with the cam surface 50, the pawl 36 may be withheld from engagement with the ratchet teeth 35 to permit the user or operator to rotate the disc 29 in a direction to reset the numbers thereon. Each time that the number-carrying disc 29 is rotated, the window 53 will be moved in proportion to the rotation of the disc 29.

By the use of a device hereinbefore described, a simple and expeditious means is provided for indicating the number of times the telephone is used.

While I have shown in the drawings a flat disc 29, it is obvious that the form of this disc is not essential to the invention and that it may be changed in form, such for example, a roller-shaped disc. By employing a roller-shaped disc the result will be the same.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An indicating device for a telephone having a receiver, comprising a housing providing a seat for the cradle of said telephone, a vertically movable member carried by said housing and movable in one direction by the weight of the receiver thereon, a ratchet bar mounted for longitudinal movement in said housing, means providing connection between said vertically movable member and said ratchet bar, means for moving said vertically movable member in an opposite direction when the weight of the receiver is removed therefrom, a spiral member within said housing and having indicating indicia thereon, means providing a connection between the spiral member and said ratchet bar whereby said spiral member will be moved step by step upon movement of said ratchet bar, and a window movably supported by the housing and having means engaging with the spiral member for movement by the latter, the indicating indicia on said spiral member being adapted to be exposed successively through said window.

2. An indicating device for a telephone having a receiver, comprising a housing providing a seat for the cradle of said telephone, a vertically movable member carried by said housing and movable in one direction by the weight of the receiver thereon, a ratchet bar mounted for longitudinal movement in said housing, means providing connection between said vertically movable member and said ratchet bar, means for moving said vertically movable member in an opposite direction when the weight of the receiver is removed therefrom, a spiral member within said housing and having indicating indicia thereon, means providing a connection between the spiral member and said ratchet bar whereby said spiral member will be moved step by step upon movement of said ratchet bar, means for rendering said means inoperative to permit said spiral

member to be manually moved in an opposite direction, and a window movably supported by the housing and having means engaging with the spiral member for movement by the latter, the indicating indicia on said spiral member being adapted to be exposed successively through said window.

3. In an indicating device, an enclosure having a longitudinal opening formed therein, a window frame mounted for movement longitudinally of said opening, a spiral member within the enclosure and having indicia thereon successively exposed through said window frame, means providing connection between said window frame and the spirals of said member whereby said window

frame will move in synchronism with said spiral member, a ratchet bar, a pawl providing connection between the ratchet bar and the spiral member, a bell crank, means providing a pivotal connection between the bell crank and the enclosure, means connecting the bell crank to the ratchet bar, an operating member, means for connecting the operating member to the bell crank, and means provided by said enclosure for supporting said operating member for movement in the direction of its length, said operating member being adapted to be moved in one direction with respect to its length by the weight of a body thereon.

16

MARK C. SMITH.
